UNITED STATES PATENT OFFICE.

FRITZ DOPP, OF BERLIN, GERMANY.

WEIGHING SCALE.

Application filed May 21, 1925. Serial No. 31,830.

To all whom it may concern:

Be it known that I, FRITZ DOPP, a citizen of the German Empire, residing at Berlin NW. 40, Germany, have invented certain new and useful Improvements in Weighing Scales; and I do hereby declare the following to be a full, clear, and exact description of the invention.

This invention relates to weighing-scales with indicator dial and pendulum weights or poises, the essential characteristic features of which weighing-scale are to be seen in the arrangement of the four balancing edges provided on both the carrying levers of the triangular type for the weighing platform, in a horizontal plane and in that the shanks of said levers are parallelly arranged one beside the other in the same direction.

In the arrangement the load exerts a pressure upon the centre of a system consisting of two steel bands provided between two pendulum levers. The angles between the arms of the counterweights and the system of steel bands are chosen in such a way, that the centre of the system of steel bands will be depressed proportionally to the increasing load. The said steel bands are passed with their ends over semi-circular segments, which are fixedly connected to one another. From the said system leads a steel band which is passed round a curved disc, the shaft of which latter is provided with a hand or pointer which moves in front of a graduated disc or dial.

In the drawing one mode of execution according to the invention is shown in which—

Figure 1 is an elevation with the casing opened;

Figure 2 is a side view of Figure 1 partly in section, and

Figures 3 to 7 show details.

Within a base *a* of the casing or frame *b* of the weighing-apparatus pans *c d* are arranged for the edges *c' d'* of both the carrying levers *e* and *f* of the triangular type, that is to say levers upon which the balancing edges are arranged in the same

plane and in a triangle, the said carrying levers being located beneath the loading platform. These carrying levers *e*, *f*, a perspective view of which is shown in Figure 3, differ from the customary carrying levers in that the four balancing edges *h* are all arranged in a horizontal plane. In addition the shanks *e'*, *f'* of the levers *e*, *f* carrying at their ends balancing edges *i* are disposed parallelly in the same direction. This result is obtained by bending the shank of the lever *e* at *e²* slightly in an upward direction.

On account of this arrangement the two carrying levers *e*, *f* will describe circular curves in equal direction, thus ensuring a great sensibility of play during the weighing operation.

In a bracket *k* secured to the frame or casing *b* an horizontal weighing lever *l* is arranged, resting with its edge *l'* in a pan *m* and carrying counterweights *l²*, *l³* and in addition a segment *l⁴*. The said weighing lever *l* is connected to the carrying levers *e*, *f* by means of two connecting rods *n*, *o*, engaging the edges *i* of the carrying levers *e*, *f*. The said rods will transfer the weight of the loaded platform *g* to the weighing lever *l*. The distance of the balancing edges of the levers is such that the same ratio of transmission will be obtained for the carrying levers.

To the segment *l⁴* of the weighing lever *l* a steel band *x* is connected, which latter will transmit the weight of the load to the pendulum weights. The edges *r* of the levers *s* of the pendulum weights rest in pans *p* provided in brackets *g*. Steel bands *u* engage the upper edges *s'* of said pendulum levers *s* by means of pan links *t* and are passed round segments *v* having semi-circular faces *v'*, and which are clamped by means of clamping plates *v²* to said segments. The two segments *v* are secured to one another by means of a suitable clamping device *w* as illustrated in Figure 4 in a vertical section, Figure 4^a a top view and Figure 5 a side view. The steel band *x* is secured to the segments *v* by means of

said clamping device w , the lower end of which steel-band is connected as stated above to the segment l^4 of the weighing-lever l .

At the lower ends of the pendulum levers s levers s^2 for the counterweights are arranged. The position of the levers s for the pendulum weights is chosen in such a manner, that the levers s^2 of the counterweights are disposed at an angle of about 45°, swinging but slightly beyond that position, and that furthermore the deflection of the two steel bands u is as uniform as possible.

A steel band x' leads from the segments v to a curved disc y wedged upon an arbor or shaft z journaled in the casing b . The steel band x' as is illustrated in Figures 1 and 2 is secured at its lower end to the clamping means w by a yoke w' and at its upper end to the periphery of the curved disc y by means of a bolt y' (Figs. 6 and 7) in such a manner that it will cause the curved disc y to effect a full revolution.

Upon the arbor z a second disc 1 is arranged which is engaged by one end of a steel band 2, the opposite end of which latter engages a lever 3 of the counterweights pivoted in the casing b at 4.

A finger 5 is attached to the shaft z and moves in front of a graduated disc or scale or dial 6, on which the weight can be read. The uniformity of the scale 6 is obtained through a corresponding position and adjustment of the segment l^4 of the lever l and through a corresponding construction of the curved disc y .

During the operation of the weighing apparatus the lever l will sink down together with the segment l^4 and the steel band x connected to the latter, pulls the steel bands u downward by means of the segments v which will cause the levers s of the pendulum weights to swing accordingly. The segments sinking down cause the shaft z to rotate through the steel band x and in consequence the finger 5 will rotate in front of the dial 6.

It is obvious that the steel bands w , x and 2 may be replaced by chains or similar devices.

I claim:

1. In weighing scales having an indicator dial and pendulum weights, the combination of a casing, substantially horizontally arranged carrying levers of the triangular type mounted within the base of the casing and having parallel shanks and load supporting edges disposed on said levers in a substantially horizontal plane.

2. A weighing-scale, comprising a casing, pendulum levers mounted in the casing and having arms carrying counter weights, carrying-levers of the triangular type having parallel ends arranged in the same plane and having load supporting edges

disposed thereon in a horizontal plane, a platform carried on said edges, and a system of steel bands connecting the pendulum levers whereby a load exerts pressure on the center of the system, the angle between the counter weight arms and the system of steel bands being such that the center of the system will be displaced in proportion equal to the increasing load.

3. A platform weighing-scale comprising a casing, pendulum levers mounted in the casing, carrying levers of the triangular type arranged beneath the platform and having parallel shanks in the same plane, said carrying levers having weighing edges disposed in a horizontal plane, load supporting edges on the levers for supporting the platform, connected segments arranged between the pendulum levers, flexible members connecting the latter to the segments, and a flexible member connected with the segments and with the carrying levers.

4. A platform weighing-scale comprising a casing, pendulum levers mounted in the casing, carrying levers of the triangular type arranged beneath the platform and having parallel shanks in the same plane, said carrying levers having weighing edges disposed in a horizontal plane, load supporting edges on the levers for supporting the platform, connected segments arranged between the pendulum levers, flexible members connected to the latter and extending around the segments, and a flexible member connected to the segments and with the carrying levers.

5. A platform weighing scale comprising a casing, an indicator dial therein, pendulum levers mounted in the casing, carrying levers of the triangular type arranged beneath the platform and having parallel shanks in the same plane, said carrying levers having weighing edges disposed in a horizontal plane, connected segments arranged between the pendulum levers, flexible members connecting the latter to the segments, a flexible member connected to the segments and with the carrying levers, a pointer movable over the dial, a flexible actuating member connected to the segments, and means connecting the pointer with the flexible actuating member.

6. A platform weighing scale comprising a casing, an indicator dial therein, a pointer movable over the dial, pendulum levers mounted in the casing, substantially horizontal carrying levers of the triangular type arranged beneath the platform and having parallel shanks, said carrying levers having weighing edges disposed in a horizontal plane, oppositely arranged connected segments located between the pendulum levers, flexible members connecting the latter to the segments, a flexible member connected to the segments and with the carry-

ing levers, a rotary member carrying the pointer, and a flexible member connected to the segments and with the rotary member.

7. In a weighing scale, a pair of substantially horizontally disposed levers each having two arms provided with pivot edges and an auxiliary arm having a balancing edge, said auxiliary arms being adjacent

and parallel, all of said edges lying in a plane, and a pair of load supporting edges on each of the two arms of the levers, all lying in the same plane.

In testimony whereof I have signed my name to this specification.

FRITZ DOPP.
